Primary Examiner—Bruce W. Dunkins*Assistant Examiner*—Janice E. Seeger*Attorney, Agent, or Firm*—James E. Brunton**[57]****CLAIM**

The ornamental design for a rocker attachment for a wheelchair, as shown and described.

DESCRIPTION

FIG. 1 is a perspective view of a rocker attachment for a wheelchair, showing my new design;

FIG. 2 is a top plan view;

FIG. 3 is a front elevational view, the rear being identical thereto;

FIG. 4 is a side elevational view, the opposite side being a mirror image thereof; and,

FIG. 5 is a bottom plan view.

FIGS. 2-5 have been drawn on an enlarged scale with respect to FIG. 1.

FIG. 1

FIG. 2

FIG. 3

FIG. 4
